(57) **CLAIM**

The ornamental design for a keyboard, as shown and described.

DESCRIPTION

FIG. 1 is a perspective view of a keyboard showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged view of portion 9 shown in FIG. 1; and,
 FIG. 10 is an enlarged view of portion 10 shown in FIG. 3. The broken lines in the drawings depict portions of the keyboard that form no part of the claimed design. The dash-dot lines encircling the detail view in FIGS. 1, 3 and 9-10 represent the bounds of the detail view and form no part thereof.

1 Claim, 10 Drawing Sheets
